UNITED STATES PATENT OFFICE.

HENRY FRANCIS KINSER, OF CHATTANOOGA, TENNESSEE, ASSIGNOR TO ARITHMETICAL SCALE COMPANY, OF CHATTANOOGA, TENNESSEE.

COMPUTING-SCALE.

SPECIFICATION forming part of Letters Patent No. 734,464, dated July 21, 1903.

Application filed July 31, 1902. Serial No. 117,894. (No model.)

To all whom it may concern:

Be it known that I, HENRY FRANCIS KINSER, a citizen of the United States, residing at Chattanooga, in the county of Hamilton and State of Tennessee, have invented a new and useful Computing-Scale, of which the following is a specification:

The invention relates to improvements in computing-scales.

10 The object of the present invention is to improve the construction of computing-scales and to provide an exceedingly simple and inexpensive one adapted to be readily adjusted to correspond with the price per pound of the 15 commodity to be weighed and capable of indicating the value of the goods weighed without requiring any mental calculation on the part of the operator.

20 A further object of the invention is to provide a computing-scale of this character having a series of beams adapted to be employed for performing mathematical calculations independently of the operation of weighing.

25 The invention consists in the construction and novel combination and arrangement of parts hereinafter fully described, illustrated in the accompanying drawings, and pointed out in the claims hereto appended.

30 In the drawings, Figure 1 is a side elevation of a computing-scale constructed in accordance with this invention. Fig. 2 is a vertical sectional view on the line 2 2 of Fig. 1. Fig. 3 is a side elevation, partly broken away, illustrating a modification of the invention. 35 Fig. 4 is a vertical sectional view of the same on the line 4 4 of Fig. 3. Fig. 5 is a side elevation of a scale, showing another form of the invention. Fig. 6 is a vertical sectional view on the line 6 6 of Fig. 5. Fig. 7 is a 40 detail view illustrating the construction of the movable price-block shown in Figs. 1, 3, and 5.

Like numerals of reference designate corresponding parts in all the figures of the drawings.

45 1 designates a frame arranged in an upright position and designed to be connected in any suitable manner with a base (not shown) of a platform-scale, and the said frame is provided with upright arms 2 and 3, located at 50 the ends of the frame and forming guides for

an upper beam. The frame is also provided with intermediate upwardly-extending arms 2^a and 3^a for supporting a horizontal bar 4, and it has an intermediate standard or support 5, preferably composed of two sides, as 55 illustrated in Fig. 2 of the drawings. The standard or support is provided at its top with arms or extensions 6, which are provided with suitable bearings for knife-edged pivots 7 of the upper or tare beam 8, fulcrumed between 60 its ends and extending through openings or slots 9 and 10 of the arms 2 and 3, whereby the upper or tare beam is limited and guided in its movement. The tare-beam, which is provided with sliding poises 11 and 11^a, has 65 slightly-curved ends and is provided thereat with knife-edged pivots 12 and 12^a for the reception of pendants 13 and 13^a, adapted to receive weights, as clearly shown in Fig. 1, for a purpose hereinafter described. 70 The tare-beam is connected in rear of the knife-edged pivots 7 by a rod 14 with platform-levers, (not shown,) and the said rod 14 has its upper portion 15 forked or bifurcated to straddle the bar 4 and a calculator-beam 75 16, which is suspended from the tare-beam 8 by links or plates 17 and which is adapted to resist any downward movement of the inner or rear arm of the same, as hereinafter explained. The links or plates are provided 80 at their ends with bearing-openings for the reception of upper and lower knife-edged pivots 18 and 19, the knife-edged pivots 18 at the upper ends of the links being also employed for connecting the rod 14 with the 85 tare-beam. The knife-edged pivots 19 of the calculator or computing beam are arranged at a point between the ends thereof, and the lower edge of its front arm is provided with notches 23, which are adapted to receive a 90 movable fulcrum 24 of a price-block 25. The price-block 25, which indicates the price per pound, is slidably mounted on the horizontal bar 4 of the frame and is adapted to be moved longitudinally thereof, and as the price of 95 the commodity increases it is moved away from the support 5, and as the price decreases it is moved inward toward the position illustrated in Fig. 1. By this arrangement the resistance offered by the computing or cal- 100

culator beam to the downward movement of the rear arm of the upper or tare beam and to the consequent poising of the scale is gradually decreased as the price-block, which indicates the price per pound, is moved outward on the graduated bar 4 away from the support. The bar 4 may be provided at its upper and lower edges with graduations, as indicated in the accompanying drawings, for increasing the range of the scale, and it may also be provided with a series of intermediate graduations, as shown. These graduations may represent units of different characters. One of the series of graduations may be provided for indicating the price per bushel of sixty pounds or the like, and another set of graduations may indicate the amount of interest per day at six per cent. or any other desired rate; but the upper or main series of graduations are designed to indicate the price per pound. This arrangement may, however, be varied, if desired. The front arm of the calculator or computing beam is provided with a sliding poise 26 and is designed to be provided with upper, lower, and intermediate graduations corresponding with those of the horizontal bar, and the rear arm of the calculator or computing beam is provided with a heavy sliding poise 26^a and has graduations corresponding with those of the said horizontal bar. The calculator or computing beam is provided at its front end with an adjustable weight. The upper or tare beam is provided at its front arm with graduations, and it has a series of removable counterbalancing-weights 28 at its front pendant 13 for counterbalancing the weight of vessels or receptacles placed on the scales for holding the goods to be weighed. The rear arm of the upper or tare beam is provided with graduations corresponding with the interest-graduations of the calculator-beam and the horizontal bar, and the pendant 12^a is provided with removable weights 28^a for increasing the range of the machine in computing interest. The calculator-beam is adapted for simple weighing operations when the price-block is at the inward limit of its movement. When it is desired to ascertain how much of a commodity may be obtained for a given amount, the price-block is arranged at the price per pound of the commodity and the sliding poises of the calculator or computing beam are arranged to indicate the amount of the purchase, and then a sufficient quantity of the commodity is placed upon the scale to bring the same to a poising-point. The price of a given quantity of a commodity may be ascertained by placing the price-block at the price per pound of the commodity and then placing the latter upon the scale and sliding the poises of the calculator-beam until the scale is brought to a poising-point. The sliding poises will then indicate the price of the commodity. Interest is calculated by arranging the price-block to indicate the number of days. The sum or principle is indicated by the rear arm

of the tare-beam and the weights of the pendant 13^a, and the scale is then brought to a poising-point by adjusting the movable weights or poises of the calculator-beam, which will indicate the amount of interest. It will be apparent that the graduations may be arranged for indicating various other results.

In order to enable the sliding price-block to be moved freely on the stationary guide-bar, the fulcrum 24 is vertically movable and is adapted to be raised and lowered to carry it into and out of engagement with the notches of a calculator-beam. The fulcrum 24 is provided with an enlarged shank 48, arranged within a vertical opening 49 of the price-block and adapted to be engaged by a cam or eccentric 50. The cam or eccentric 50 is formed by recessing or cutting away a pivot or shaft 51, which extends through the price-block at opposite sides of the said opening 49 and which is adapted to be rotated to carry the cam into and out of engagement with the lower end of the shank of the fulcrum 24. The pivot or spindle is provided at its outer end with a knob or thumb-piece 52 and is adapted to be rotated to operate the cam or eccentric 50 for raising and lowering the fulcrum 24. By this construction the fulcrum is adapted to be readily lowered to carry it out of engagement with the notches of the calculator-beam to permit it to be adjusted along the stationary graduated bar, and after the price-block has been adjusted and arranged at the proper point the fulcrum may be quickly raised to its engaging position.

In Fig. 3 of the drawings is illustrated a modification of the invention wherein the central support is omitted and the tare-beam 29 is located at the bottom of the frame and is fulcrumed between its ends by a suitable knife-edged pivot 30. The rear end of the tare-beam 29 is connected by a suitable knife-edged pivot 31 with the sides of the forked or bifurcated upper portion of the rod 14^a, which extends to the platform-levers. The calculator-beam is suspended by suitable links or plates 31^a from the sides of the forked or bifurcated portion of the rod 14^a. The links or plates 31^a are connected at their upper ends to the sides of the said forked portion of the rod 14^a, and the lower ends of the links or plates 31^a are similarly connected with the calculator-beam. The front end of the beam 29 is provided with an adjustable weight 32, and the operation of the calculator or computing beam and the price-block is similar to that heretofore described.

In Figs. 5 and 6 of the drawings is illustrated another form of the invention, in which a calculator-beam, a fixed horizontal bar, and a sliding price-block similar to those heretofore described are employed. The tare-beam 33 is arranged at the top of the scale and is fulcrumed, by means of a knife-edged pivot 34, on a support 35, constructed similar to that illustrated in Fig. 1 of the drawings.

The inner or rear end of the tare-beam is connected with a rod 36, which is designed to extend to the platform-levers, (not shown,) and the said inner or rear end of the tare-beam is also connected by plates or links 37 with the calculator-beam, as described in connection with the form of scale shown in Figs. 1 and 2. This form of scale differs from that shown in Fig. 1 in that a heavy sliding value-poise is omitted, and the calculator-beam is provided at its front end with a pendant 38, having a series of weights for indicating the value. The calculator-beam 39, which is connected with the upper or tare beam by links 15 or plates 40, is provided at its lower edge with a series of notches 41 to receive a fulcrum 42 of a sliding price-block 43, which is mounted on a horizontal bar 44. The calculator-beam in this form of scale is designed to be of an increased length, and in order to facilitate the arrangement of the sliding poise an intermediate beam 45 is employed. The intermediate beam 45, which receives the sliding poise 46, is balanced when the latter is at the inner end of the graduations or at zero-point, and the outer end of the intermediate beam 45 is connected with the outer end of the calculator-beam by a link or links 47. The value-graduations are marked off on the intermediate beam, and the scale operates substantially the same as those heretofore described in ascertaining the price of a commodity or the quantity of the same to be given for a certain sum.

Changes in the form, proportion, size, and the minor details of construction within the scope of the appended claims may be resorted to without departing from the spirit or sacrificing any of the advantages of this invention, such as connecting the rod 14 with any suitable means for receiving the goods to be weighed.

What I claim is—

1. In a computing-scale, the combination 45 of a frame having a fixed graduated price-bar, a sliding price-block arranged on the graduated bar and having a non-tiltable fulcrum, a computing-beam having a movable poise and located directly above and adapted to fulcrum on the price-block, and a tare-beam connected with the calculator-beam and designed to be connected with the goods to be weighed, substantially as described.

2. In a computing-scale, the combination 55 of a frame having a fixed graduated price-bar, a sliding price-block arranged on the graduated bar and having a non-tiltable fulcrum, a computing-beam having a sliding poise and located directly above and fulcrumed on the price-block, a tare-beam having a movable poise and designed to be connected with the goods to be weighed, and means for connecting the tare-beam with the calculator-beam, substantially as described.

65 3. In a computing-scale, the combination of a frame having a fixed graduated price-bar, a movable price-block arranged on the

graduated bar and having a non-tiltable fulcrum, a computing-beam located directly above and adapted to be fulcrumed on the 70 price-block, and a tare-beam connected with the computing-beam, substantially as described.

4. In a computing-scale, the combination 75 of a frame having a fixed graduated price-bar, a computing-beam located above the graduated price-bar, a movable price-block arranged on the graduated bar and provided with a non-tiltable fulcrum located directly beneath the computing-beam and arranged to 80 receive the same, a tare-beam located above and connected with the computing-beam, and movable poises arranged on the said beams, substantially as described.

5. In a computing-scale, the combination 85 of a frame having a fixed graduated bar, a tare-beam fulcrumed between its ends on the frame and having a movable poise, a calculator-beam connected with the tare-beam, and a movable price-block arranged on the 90 graduated bar and provided with a non-tiltable fulcrum located directly beneath and arranged to receive the calculator-beam, substantially as described.

6. In a computing-scale, the combination 95 of a frame having a fixed graduated bar and provided with a support, a tare-beam fulcrumed between its ends on the support and having a poise, a rod connected with the tare-beam and designed to be connected with the 100 goods to be weighed, a calculator-beam located between the tare-beam and the graduated bar and having a poise, links connecting the calculator-beam and the tare-beam, and a price-block arranged on the graduated 105 bar and provided with a non-tiltable fulcrum located directly beneath and arranged to receive the calculator-beam, substantially as described.

7. In a computing-scale, the combination 110 of a frame, a tare-beam fulcrumed between its ends thereon and provided with opposite sliding poises and having weight-receiving pendants at its ends, a calculator-beam connected between its ends with the tare-beam 115 and provided with opposite movable poises, and a movable price-block provided with a non-tiltable fulcrum located directly beneath and arranged to receive the calculator-beam, substantially as described. 120

8. In a computing-scale, the combination 125 of a frame, a calculator-beam provided at its lower edge with notches, a movable price-block located directly beneath and forming a non-tiltable fulcrum for the calculator-beam and provided with a vertically-movable fulcrum portion adapted to be carried out of engagement with the notches of the calculator-beam to permit the price-block to slide freely, and a beam connected with the calculator-beam and designed to be connected with the 130 goods to be weighed, substantially as described.

9. In a computing-scale, the combination

of a frame, a calculator-beam provided with notches, a movable price-block provided with a vertically-movable fulcrum arranged beneath and adapted to receive and engage the 5 notches of the calculator-beam to form a non-tiltable fulcrum for the latter, a rotary cam or eccentric mounted on the price-block for operating the movable fulcrum thereof, and a beam connected with the calculator-beam

and designed to be connected with the goods to be weighed, substantially as described.

In testimony that I claim the foregoing as my own I have hereto affixed my signature in the presence of two witnesses.

HENRY FRANCIS KINSER.
